Fig. 4

Fig. 5

Fig. 1 is a perspective view of a pneumatic tire embodying our new design, it being understood that the full line portion is repeated throughout the circumference of the tire shown by means of broken lines;

Fig. 2 is an enlarged fragmentary perspective view;

Fig. 3 is an enlarged fragmentary plan view of the full line portion of Fig. 1;

Fig. 4 is a sectional view taken substantially on the plane indicated by line IV-IV of Fig. 3; and

Fig. 5 is a detailed sectional view taken substantially on the plane indicated by line V-V of Fig. 2.

The dominant features of our design reside in those portions shown in full lines in the drawings.

We claim:

The ornamental design for a pneumatic tire, substantially as shown and described.
